CLAIM

The ornamental design for an electronic paper dispenser assembly as shown and described.

DESCRIPTION

FIG. 1 is a front view of the base of the electronic paper dispenser assembly showing the dispenser portion isolated from the leaf portion to show aspects of the design not visible in the assembled state.

FIG. 2 is a back perspective view thereof.

FIG. 3 is a right side perspective view thereof.

FIG. 4 is a left side perspective view thereof.

FIG. 5 is a perspective view of the electronic paper dispenser assembly, shown in an assembled state; and,

FIG. 6 is a bottom perspective view of the electronic paper dispenser assembly as shown in FIG. 1.

All broken lines in the drawings depict portions of the electronic paper dispenser assembly that form no part of the claim.

1 Claim, 6 Drawing Sheets
